INVALID BATHING LIFT FOR BATHTUBS OR THE LIKE

Benton H. Grant, Stamford, Conn., and Trevor W. Denzey, Toronto, Ontario, Canada, assignors to Grant Airmass Corporation, Stamford, Conn.

Filed July 20, 1971, Ser. No. 164,493

Term of patent 14 years

Int. Cl. D24—01

U.S. Cl. D83—1

FIG. 1

FIG. 2

FIG. 3

FIG. 4

FIG. 5

FIG. 1 is a top plan view of a bathtub lift showing our new design wherein the seat has been rotated to one side and is in a lowered position.

FIG. 2 is a front elevation view thereof.

FIG. 3 is a side elevation view thereof with the seat shown in an elevated position.

FIG. 4 is a rear elevation view thereof.

FIG. 5 is the opposite side elevation view thereof with the seat shown in a lowered position.

We claim:

The ornamental design of an invalid bathing lift for bathtubs or the like, as shown.
